(57) **CLAIM**

The ornamental design for a tool box, as shown and described.

DESCRIPTION

FIG. 1 is a top perspective view showing our new design for a tool box;

FIG. 2 is a front elevational view of the tool box of FIG. 1; FIG. 3 is a rear elevational view of the tool box of FIG. 1; FIG. 4 is a right side elevational view of the tool box of FIG. 1, the left side elevational view being a mirror image thereof;

FIG. 5 is a top plan view of the tool box of FIG. 1; FIG. 6 is a bottom plan view of the tool box of FIG. 1; and, FIG. 7 is a bottom isometric view of the tool box of FIG. 1. The translucent grey overlay and the broken lines in the drawings depict portions of the tool box that form no part of the claimed design.
